UNITED STATES PATENT OFFICE.

ANDREW MORRISON, OF PENN TOWNSHIP, ALLEGHENY COUNTY, PENNSYLVANIA,
ASSIGNOR TO DILWORTH, PORTER & COMPANY, INCORPORATED, OF PITTSBURGH,
PENNSYLVANIA, A CORPORATION OF PENNSYLVANIA.

TIE-PLATE.

1,357,178.

Specification of Letters Patent. Patented Oct. 26, 1920.

Application filed July 30, 1919. Serial No. 314,240.

To all whom it may concern:

Be it known that I, ANDREW MORRISON, a citizen of the United States, residing at Penn township, in the county of Allegheny and State of Pennsylvania, have invented a new and useful Improvement in Tie-Plates, of which the following is a full, clear, and exact description, reference being had to the accompanying drawings, forming part of this specification.

The present invention relates broadly to tie plates for rails and has for its principal object to provide a tie plate having intersecting ribs formed on the bottom thereof, and so located that a reinforced tie plate is produced.

Another object of the present invention is to provide a tie plate having longitudinally and transversely extending ribs, all of which are spaced from the respective edges of the tie plate.

A further object of the present invention is to so position the spike openings in the tie plate that water passing therethrough will be drawn by capillary attraction from under the tie plate, whereby the surface of the tie lying directly beneath the tie plate is prevented from rotting.

A still further object of the present invention is to provide a tie plate having a plurality of suction or holding squares or spaces formed thereon, tending to securely anchor the tie plate in position.

The foregoing and other objects, together with their attendant advantages, will be apparent as the invention becomes better understood by reference to the accompanying specification and drawings forming a part thereof, it being premised that changes may be made in the various details and the manner of operation within the scope of the appended claims without departing from the spirit of the invention.

Figure 1 is a sectional view illustrating a rail in position on a tie plate and showing diagrammatically the force produced by a wheel traveling over the rail.

Fig. 2 is a bottom view of the tie plate illustrated in Fig. 1.

It has heretofore been proposed to construct tie plates having longitudinally and transversely extending ribs formed on the bottom thereof. With such construction, however, it has been common to have the

outermost ribs extending around the periphery of the tie plate. When so positioned, if the tie plate were used on a narrow tie, splitting of the tie resulted and water-receiving grooves were formed entirely around the tie plate.

It has also been proposed to provide tie plates with diagonally extending intersecting ribs but in actual use, it has been found that ribs so positioned do not effectively resist the creeping action or spreading action of the rails. I am also aware that tie plates have been constructed in which V-shaped ribs have been formed on the base thereof, but with constructions of this nature the reinforcing action desirable and the anti-creeping action has not been secured. The present invention is particularly designed to overcome the objections to tie plates as ordinarily constructed and to provide a tie plate having ribs extending in a particular manner whereby creeping is effectively prevented and a reinforcing at the desired point is produced.

Referring more particularly to the drawings: I have illustrated a suitable tie 2 having my improved tie plate 3 in position thereon. In its preferred embodiment, the tie plate comprises an upper rail-receiving surface 4 having a transversely extending abutment 5 defining one limit thereof. Resting on the rail-receiving surface 4, and held in position by suitable spikes or the like 6, extending through the opening 7, is a rail 8.

It is highly desirable in a construction of this nature to have the openings 7 so positioned that they extend entirely into the partially unobstructed outermost spaces formed between the projecting ribs 9. By reason of such arrangement, any moisture which works through the openings is free to be drawn outwardly from beneath the tie plate. It will be apparent that where peripheral projecting ribs are provided, such escape of water is prevented. Also, in the present construction, by having the outermost longitudinally and transversely extending ribs spaced from the respective edges of the tie plate, substantially flat bearing surfaces are provided adjacent such edges so that the fiber of the tie is not broken.

The ribs provided on the present tie plate not only prevent lateral movement of the plate, which would result in separation of the

rails, and longitudinal movement produced by setting the brakes on the train, but, by reason of their particular position, serve as reinforcing means for the tie plate. It has been found that in actual use a tie plate is subject to two predominating forces. These forces have been illustrated diagrammatically by means of arrows in Fig. 1, in which figure the arrow A represents the direction of the affective force exerted by the flanged wheels, the arrow A' represents the affective force produced by the load carried by the wheels, and the arrow A² represents the resultant of these forces. This resultant force is transmitted to the tie plate in the manner indicated by the dotted arrow A², tending to break the tie plate in the plane of the line of intersection between the abutment 5 and the rail supporting surface 4. In order to overcome this action, I form one of the transversely extending ribs 9 directly below this line of intersection so that means are provided for directly sustaining the load adjacent one of the base flanges of the rail. In order to directly sustain the load of the opposite side of the base flange of the rail, I position another of the transversely extending ribs so that it occupies a position substantially directly beneath the edge of the rail flange when placed thereon. Still another of the transversely extending ribs is illustrated as formed intermediate the ribs referred to so that a direct support for the web of a rail is insured.

The longitudinally extending ribs intersecting the transversely extending ribs before described, form suction squares or spaces 10, substantially centrally of the tie plate. These spaces have unbroken ribs surrounding the same, effectively coöperating with the projecting ribs for maintaining the tie plate in proper position on the tie.

The broad bearing surfaces provided around the edges of the tie plate, coöperating with the particular manner of reinforcing,

ing, insure a rigid tie plate which will withstand the forces and loads to which it is subjected, and which will prevent displacement of the rails.

I claim:

1. As an article of manufacture, a tie plate having an upper rail receiving surface, a rail abutment extending transversely of the plate, a transversely extending rib formed on the lower surface of the plate directly beneath the line of junction of the abutment with the plate to directly sustain the load of one edge of the base flange of the rail, a second transversely extending rib formed on the lower surface of the plate to directly sustain the load of the other edge of the base flange of the rail, a third transversely extending rib intermediate said first mentioned ribs for directly sustaining the load through the web of the rail, and similarly shaped longitudinally extending ribs intersecting said transversely extending ribs and forming a plurality of centrally located section-spaces; substantially as described.

2. As an article of manufacture, a tie plate having an upper rail receiving surface, a rail abutment extending transversely of the plate, a transversely extending rib formed on the lower surface of the plate directly beneath the line of junction of the abutment with the plate to directly sustain the load of one edge of the base flange of the rail, a second transversely extending rib formed on the lower surface of the plate to directly sustain the load of the other edge of the base flange of the rail, a third transversely extending rib intermediate said first mentioned ribs for directly sustaining the load through the web of the rail, and longitudinally extending ribs forming substantially centrally located suction spaces, all of said ribs being of uniform cross sectional area throughout their length; substantially as described.

In testimony whereof, I have hereunto set my hand.

ANDREW MORRISON.
